ALBERT E. DEAN AND LE BEAU GRUNDY, OF FALL RIVER, MASSACHUSETTS, ASSIGNEES TO DRAPER CORPORATION, OF HOPEDALE, MASSACHUSETTS, A CORPORATION OF MAINE.

LAY-ROCK-SHAFT BEARING FOR LOOMS.

Application filed November 14, 1925. Serial No. 69,060.

This invention relates to lay rock shaft bearings for looms whereby the lay rock shaft is supported in proper position for controlling the path of movement of the lay. It is now the common practice to provide the side frames of a loom with separate bearings for supporting the lay rock shaft, and such bearings are usually secured to the side frames of the loom for adjustment to take up wear incident to the rocking movement of the lay rock shaft.

During weaving, however, the lay is frequently subjected to a thrust, usually in an upward direction, when the loom "bangs off" and such thrust is caused by the combined action of the dagger when the shuttle fails to box properly and the pitman connection between the lay and crank shaft. Such thrust upon the lay rock shaft frequently results in displacement of the lay rock shaft bearings, and one of the objects of the present invention is to provide a lay rock shaft bearing which will effectively withstand such thrusts to which the lay is subjected at times, without disturbing the adjusted condition of the bearing itself.

In accordance with the present invention, the lay rock shaft bearing comprises side arms and a central bearing hub having extending from its upper and lower surfaces thrust lugs of similar character which take the thrust of the lay rock shaft when the loom bangs-off. In the preferred form of the present invention, the entire thrust bearing, including the thrust lugs, is formed as a single casting, and the thrust lugs themselves project from the upper and lower surfaces of the central hub bearing at a point adjacent the connection between such bearing and the side arms.

The invention and new combination of parts will best be made clear from the following description and the accompanying drawings of one good form thereof.

In the drawings:

Fig. 1 is a perspective view showing the parts of a loom associated with the present invention;

Fig. 2 is a side elevation, some of the parts being shown in section;

Fig. 3 is a front elevation with parts shown in section; and

Fig. 4 is an enlarged perspective detail showing the lay rock shaft bearing containing the present invention.

55

As herein shown, only one side frame of the loom and a single rock shaft bearing is shown, it being understood that the opposite side of the loom is similarly constructed.

The side frame 1 of the loom is provided with the usual flanges 2 and 3 and at the lower part of the loom frame the web connecting the flanges 2 and 3 is provided with a vertical elongated opening 4 through which the lay rock shaft 5 extends. Inside 65 of the side frames of the loom, the lay rock shaft 5 is provided with the usual lay swords 6, on the upper portions of which the lay is mounted, as usual, and the lay, as is common in loom constructions, is given a movement 70 towards and from the front of the loom. The lay, of course, carries the usual shuttle boxes and dagger knock-off, which features, however, form no part of the present invention, and as they are now well understood 75 in the art illustration thereof seems unnecessary.

The lay rock shaft bearing which forms the subject of the present invention comprises the side arms 7 and 8, each of which is provided with an opening 9 through which passes the usual securing bolts 10 which connect the lay rock shaft bearing with the loom frame. Extending from the face of the side arms 7 and 8 is the central bearing hub 11 which is of less cross-sectional dimension than the elongated opening 4 in the side frame of the loom, and, as shown, the central bearing hub 11 extends through the elongated opening 4 and is secured in place 80 as above indicated by the securing bolts 10.

The central bearing hub 11 is provided with a bushing 12 through which extends the lay rock shaft 5, as shown in Fig. 3. It is usual to mount upon the end of the lay rock shaft 5 the picker stick support or bearing 13, Fig. 1, on which the picker stick 14 is mounted, but as such features form no part of the present invention, further description is unnecessary.

It is frequently desirable to adjust the lay rock shaft bearing, especially when the parts become worn, in order that the lay rock shaft itself may be given its proper position to

cause the lay to move in the desired path. To this end the side frames of the loom are provided with the vertical openings 15, which cross the openings 9 in the side arms 5 when the parts are assembled as indicated at 16, Fig. 2. The vertical slots 15 are provided to permit the lay rocker shaft bearings carrying the central bearing hub 11 to be adjusted vertically while the horizontally 10 extending slots are provided to accommodate a horizontal adjustment of the lay rocker shaft bearing.

As shown in the present instance of the 15 invention, the side surface portions of the central bearing hub 11 are flattened or cut away, as at 17, thereby permitting lateral adjustment of the bearing when necessary, and since the vertical dimension of the central bearing hub is less than the elongated 20 opening 4 in the side frame of the loom, provision is made for vertical adjustment of the lay rock shaft bearing.

In accordance with the present invention, 25 the central bearing hub is provided with oppositely extending, integral thrust lugs or projections which extend into the elongated opening 4 in the side frame of the loom and one of which lugs bears upon the upper surface of such opening, thereby taking up any thrust in an upward direction which may be exerted upon the bearing at times, as when the loom bangs-off.

As more particularly indicated in Fig. 4, 30 the central bearing hub 11 has a thrust lug or projection 18 extending upwardly from its upper surface, and a similar thrust lug 19 at its lower surface.

The two thrust lugs 18 and 19 do not extend about the central bearing hub but project only from the upper and lower surfaces thereof, and each of said thrust lugs is formed integral with the side arms 8 and the central bearing hub 11 and tapers from the axis of the central bearing hub 11. In the 45 present instance, each of the thrust lugs 18 and 19 is provided with inclined surfaces 20 and 21.

When the lay rock shaft bearing is in operative position, as indicated in Figs. 1, 2 50 and 3, the top edge portion of the upper thrust lug 18 rests against the upper surface of the elongated opening 4 formed in the side frame of the loom, with the result that should the lay impart an upward lifting or thrust action upon the lay rock shaft, as when the loom bangs-off, such thrust will be taken up by the upper thrust lug 18 without disturbing the adjustment of the lay rock shaft bearing on the loom frame. By 55 making the thrust lugs 18 and 19 of similar form and size, the lay rock shaft bearing as a whole is made reversible; that is, the lay rock shaft bearing, as indicated in Fig. 4, 60 may be applied to the loom frame and to the lay rock shaft with either the thrust lug 65

18 or the thrust lug 19 in upper position to bear against the upper surface of the elongated opening 4 in the loom frame.

Since the horizontal dimension of the central bearing hub 11 is less than the corresponding dimension of the opening 4 in the loom frame, the lay rock shaft bearing may be adjusted laterally. When, however, the lay rock shaft bearing or the lay rock shaft itself becomes worn, and vertical adjustment of the lay rock shaft bearing is desired, the upper thrust lug 18 in the present showing, may have its upper edge portion trimmed off or filed to provide the necessary upward adjustment of the lay rock shaft bearing.

In assembling the parts, the central bearing hub 11 of the lay rock shaft bearing is extended through the elongated opening 4 in the side frame, with the top edge of the thrust lug then in upper position bearing against the upper surface of the opening 4. The lay rock shaft bearing is then secured in position by the usual securing bolts 10, so that on the occurrence of an upward thrust 90 to the lay rock shaft occasioned by a bang-off of the loom, the upper thrust lug will absorb the disturbing force and prevent displacement of the lay rock shaft bearing. So, also, when a vertical adjustment of the lay 95 rock shaft bearing is desired and the upper thrust lug is trimmed off as above explained, it will be brought into contact with the upper surface of the opening 4 when the parts are reassembled, so that in both new and worn bearings, the upper thrust lug serves to prevent displacement of the lay rock shaft bearing and, consequently, the lay, whenever a bang-off or other upward thrust occurs.

What is claimed is:

1. In a loom, the combination of the side frame having an opening to receive the hub of a lay rocker shaft bearing, a lay rocker shaft bearing having a central bearing hub adapted to be mounted in said opening and having oppositely extending arms adapted to be secured to the side frame in different positions of adjustment, a lay rocker shaft journaled in the hub, and integral thrust lugs projecting at the top and bottom of the bearing hub within said opening and formed so that when either side of the hub is turned upward one of the lugs will abut against the upper inner wall of the opening to receive the vertical thrust exerted upon the lay 110 rocker shaft when the loom "bangs off".

2. In a loom, the combination of the side frame having an opening to receive the hub of a lay rocker shaft bearing, a lay rocker shaft bearing having a central bearing hub adapted to be mounted in said opening and having oppositely extending arms adapted to be secured to the side frame in different positions of adjustment, a lay rocker shaft journaled in the hub, an integral thrust lug 125

projecting upwardly from the top of the bearing hub within said opening to abut against the upper wall of said opening to receive the vertical thrust exerted upon the 5 lay rocker shaft, and the lug being formed with a narrow bearing edge that may be readily cut away to facilitate vertical adjustment of the hub.

3. A lay rocker shaft bearing formed as a 10 single casting and comprising a central bearing hub having oppositely extending side arms adapted to be clamped to the side

frame of a loom in different positions of adjustment, and the central bearing hub being provided at its top and bottom with integral 15 thrust lugs adjacent the side arms and which have narrow bearing edges that may be readily cut away to facilitate vertical adjustment of the hub upon the loom frame.

In testimony whereof, we have signed our 20 names to this specification.

ALBERT E. DEAN.
LE BEAU GRUNDY.
